DESIGN FOR A FUR SEWING MACHINE

Thomas C. Mladinich and Salvatore Nicosia,
New York, N. Y.

Application February 10, 1939, Serial No. 82,908

Term of patent 14 years

To all whom it may concern:

Be it known that we, Thomas C. Mladinich and Salvatore Nicosia, citizens of the United States, residing at New York, in the county of New York and State of New York, have invented a new, original, and ornamental Design for a Fur Sewing Machine, of which the following is a specification, reference being made to the accompanying drawing, forming part thereof.

Figure 1 is a view showing an end elevation of a fur sewing machine showing our new design.

Figure 2 shows a front elevation of the machine with the looper arm omitted.

Figure 3 is an end elevation looking in the opposite direction to that shown in Figure 1.

Figure 4 is a plan view of the machine with the looper arm omitted.

We claim:

The ornamental design for a fur sewing machine, as shown and described.

THOMAS C. MLADINICH.
SALVATORE NICOSIA.
